UNITED STATES PATENT OFFICE.

ANDREW J. SANFORD, OF NEWARK, OHIO, ASSIGNOR TO A. H. HEISEY & CO., INC., OF NEWARK, OHIO, A CORPORATION OF WEST VIRGINIA.

DESIGN FOR A LIGHT-SHADE.

40,944.

Specification for Design.

Patented Oct. 18, 1910.

Application filed August 16, 1910. Serial No. 577,532. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

In the drawings Figure 1 is a perspective view of a light shade showing my new design; and Fig. 2 is a bottom plan view of the same.

The leading features of my design consist

in a shade of general truncated cone form having a concave circular neck portion, and an ornamentation below the same comprising a series of convex longitudinally extending facets, and below the same another series of prisms, as shown.

I claim:

The ornamental design for a light shade, as shown and described.

ANDREW J. SANFORD.
